Patented Oct. 7, 1913.

UNITED STATES PATENT OFFICE.

ROBERT L. COONEY, OF ATLANTA, GEORGIA.

CHEMICAL-MIXING FIRE-EXTINGUISHER SYSTEM.

1,075,018.

Specification of Letters Patent.

Patented Oct. 7, 1913.

Application filed June 15, 1910. Serial No. 567,048.

To all whom it may concern:

Be it known that I, ROBERT L. COONEY, a citizen of the United States, residing at Atlanta, in the county of Fulton and State 5 of Georgia, have invented new and useful Improvements in Chemical-Mixing Fire-Extinguisher Systems, of which the following is a specification.

The present invention is an improvement 10 in the chemical mixing apparatus of stationary fire extinguisher systems of the general type illustrated in my co-pending application, Serial No. 530,470 and it proposes a novel self-contained organization of the 15 acid bottle and the parts which control the operation thereof.

The objects of the invention are to provide for more ready accessibility to the operating parts; to provide also for a more 20 facile recharging of the system and resetting of the parts after an operation thereof; and to improve the operation of the system in respects which will be particularly pointed out.

25 An embodiment of the invention is illustrated in the accompanying drawings wherein:

Figure 1 is an enlarged detail sectional view illustrating the normal relations of the 30 parts; Fig. 2 is an elevation on a similar scale showing the relation of the parts during the discharging operation of the acid bottle; Fig. 3 is a top plan view of the frame in which the acid bottle is mounted; 35 and Fig. 4 is a side elevation thereof.

Similar characters of reference designate corresponding parts throughout the several views.

The type of system to which the invention 40 is especially applicable, includes a tank, as 1, containing an alkaline solution, a distributing pipe, as 2, which projects into the tank, an acid bottle, as 3, which, at the time of a fire is caused to discharge its contents into 45 the body of solution, a piston latch, as 4, which normally prevents the discharging operation of the acid bottle and is operable at the time of a fire by a pneumatic impulse to provide for the discharging operation of 50 the acid bottle, a cylinder, as 5, with respect to which the piston latch is axially movable, and a pipe or tube section, as 6, which puts the cylinder 5 in communication with the distributing pipe. Access to 55 the interior of the tank 1 is had through an

opening, as 7, which is normally covered by a closure plate, as 8.

The pipe or tube section 6 projects upwardly in the distributing pipe coaxially thereof and has a branch, as 6^a, which projects laterally from the distributing pipe into the tank. The distributing pipe forms one support for the branch 6^a, and the latter is additionally supported, as by a ring or hook 9, which is secured in the wall of 60 the tank. The branch 6^a terminates in an upturned end portion, as 10, which projects into the opening 7, is of tapering contour, and has a ground face.

In the embodiment shown, the acid bottle 70 is pivotally mounted off center in a rectangular frame, as 11, and the latter which is removably supported in the tank carries the associated operating parts. The acid bottle is of such construction that its upper portion 75 is of considerably greater weight than its lower portion and this, coupled with the arrangement of its pivots, provides for a complete reversal of the acid bottle during its discharging operation. The weighting 80 of the upper portion of the acid bottle, while an objective feature, may be an incident of certain other advantageous features of construction in which additional walls are required in the upper portion of the acid bottle. 85 These "other" features which are the initial and subsequent discharging chambers 3^a and 3^b and a drainage chamber, as 3^c, which surrounds the chamber 3^a, have no relation, *per se*, in a patentable sense to the 90 present invention. The cylinder 5 is secured at the top of the frame 11 and on its upper face is provided with a transverse projection 12 which serves the threefold purpose of a handle, of a hanger, and of a 95 continuation of the branch 6^a. With regard to the purpose of the projection 12 as a handle, it will be noted that said projection extends beyond the cylinder 5 at opposite 100 sides thereof and that the extending portions provide a convenient hand grip. With regard to the purpose of the projection 12 as a hanger, said projection has at one end thereof a socket, as 13, which fits over the upturned end portion 10 of the branch 6^a, 105 and the other end of the projection 12 seats against a lug, as 14, which projects inwardly from the edge of the opening 7. With regard to the purpose of the projection 12 as a continuation of the branch 6^a, 110

the internal face of the socket 13 is of tapering outline, exactly conforming to the external face of the upturned portion 10 of the branch 6^a and is moreover ground so as to have a gas-tight sealing engagement with the face of said upturned end portion 10; and said projection is provided with a duct 15 which communicates with the duct of the end portion 10 of the branch 6^a and which also communicates with the interior of the cylinder 5. The mouth of the duct 15 which communicates with the cylinder 5 is co-axial with said cylinder and of flaring outline, as at 16, for a purpose which will presently appear.

15 The cylinder 5 is preferably provided at its lower end with an internal jacket, as 17, and the piston of the piston latch is of cup-shaped outline, its annular portion working in the jacket. The latter constitutes an efficient guide for the piston and is advantageously filled with oil or glycerin to prevent corrosion, to reduce friction, and to provide a seal against the escape of gas past the piston. The piston is provided on its upper side with a centrally located axial projection, as 18, which is of tapering outline and which is arranged to engage in the flaring mouth 16 of the duct 15 under circumstances to be described and to thus seal the mouth of the duct against the passage of any gas which might leak into the cylinder.

35 The acid bottle is preferably normally closed by a loose fitting stopper, as 19, recessed in its under face to receive the upper edge portions of the walls of the acid bottle and having also a central recess in its upper face in which the stem of the piston latch is 40 has latching engagement. The stopper 19 is preferably connected to the cylinder 5, as by a chain 20.

45 During the operation of the system it is preferred to positively hold the piston latch in its uppermost position and for this purpose a suitable projection, *e. g.* a bow spring, as 21, is provided on the bottom of the acid bottle and when the latter is completely inverted, as in Fig. 2, the projection 21 will 50 engage the stem of the piston latch and positively hold the latter in its uppermost position, sealing the mouth of the duct 15, as shown.

55 As was stated above, the piston is operated by a pneumatic impulse. There are several ways in which this impulse may be developed. A preferred way, however, consists in charging the distributing system and the tank with pressure which is confined 60 until the event of the fire. In this case the pressure in the system and the pressure in the tank must be kept equal, and for this purpose the cylinder 5 is provided with a very small opening, as 22. This opening 65 will pass pressure from the tank to the

system or from the system to the tank in the event of leakage at any point and hence will maintain the pressures equal at all times. But when the pressure in the distributing system is suddenly exhausted or 70 suddenly and materially reduced as at the time of a fire consequent to the opening of a sprinkler head or distributing valve, the opening 22, owing to its small diameter, will not pass any material portion of the 75 pressure in the tank and consequently the tank pressure being thus unrestrained, acts to force the piston latch to its uppermost position. Thereupon the stem of the piston latch is withdrawn from engagement 80 with the loose fitting stopper 19 and the acid bottle overturns by gravity, discharging its contents into the body of solution and bringing its projection 21 into engagement with the stem of the piston latch, 85 whereby the latter is held in its uppermost position sealing the mouth of the duct 15 against the passage of any of the developed gas which might be otherwise passed into the distributing system in advance of the 90 outgoing column of liquid, through the duct 15 and the opening 22. The advantage of this action resides in the fact that it eliminates any "sputtering" which would otherwise take place at the open sprinkler head 95 or hose nozzle with consequent impairment of the force and the efficiency of the stream.

To recharge the system and reset the parts, the closure plate 8 is removed and the entire self-contained organization is lifted 100 from the tank through the opening 8. The tank is thereupon partially filled with the alkaline solution and the acid bottle is filled in any convenient manner, after which the stopper 19 is placed in position and the piston latch reset. The self-contained organization is thereupon replaced in the tank through the opening 7 and hung in position in the manner explained. The organization of the parts in this manner not only 110 provides for a more facile recharging of the system but it facilitates renewals and repairs, by providing for instant and perfect accessibility to the operating parts from the exterior of the tank.

115 Having fully described my invention, I claim:

1. In a chemical mixing fire extinguisher system, a tank containing an alkaline solution, an acid bottle, a piston operable by a 120 pneumatic impulse and having means to control the discharging operation of the acid bottle, a piston cylinder, a frame carrying the acid bottle, the piston, and the piston cylinder and removably supported 125 in the tank, a distributing pipe leading from the tank, and a pipe whereby said cylinder may communicate with said distributing pipe when the frame is supported in the tank.

2. In a chemical mixing fire extinguisher system, a tank containing an alkaline solution, an invertible acid bottle, a piston latch normally holding the acid bottle in its upright position and operable by a pneumatic impulse to disengage the acid bottle, a cylinder for the piston latch, a frame carrying the acid bottle, the piston latch and the cylinder and removably supported in the tank, a distributing pipe leading from the tank, and a pipe whereby said cylinder may communicate with said distributing pipe when the frame is supported in the tank.

3. In a chemical mixing fire extinguisher system, a tank containing an alkaline solution, a distributing pipe communicating with the tank, a pipe section arranged in the distributing pipe and having a branch which projects laterally from the distributing pipe into the tank, an acid bottle, a piston operable by a pneumatic impulse and which governs the discharging operation of the acid bottle, a piston cylinder having means removably associated with the branch and for putting the cylinder into communication with the branch, and a frame carrying the acid bottle, the piston and the cylinder and removably supported in the tank.

4. In a chemical mixing fire extinguisher system, a tank containing an alkaline solution, an invertible acid bottle, a piston latch normally holding the acid bottle in its upright position and operable by a pneumatic impulse to disengage the acid bottle, a cylinder for the piston latch, a projection extending across the top of the cylinder and having a socket at one end thereof and a duct extending between the socket and the cylinder, a pipe section arranged in the distributing pipe and having a branch which projects laterally from the distributing pipe into the tank and terminates in an upturned end portion over which the socket may be fitted, and a frame carrying the acid bottle, the piston latch and the cylinder and removably supported in the tank.

5. In a chemical mixing fire extinguisher system, a tank containing an alkaline solution, an invertible acid bottle, a piston latch normally holding the acid bottle in its upright position and operable by a pneumatic impulse to disengage the acid bottle, a cylinder for the piston latch, a projection extending across the top of the cylinder and having a socket at one end thereof and a duct extending between the socket and the cylinder,

the piston of the piston latch having a projection to engage in and seal the mouth of the duct when the piston latch is in its uppermost position, a pipe section arranged in the distributing pipe and having a branch which projects laterally from the distributing pipe into the tank and terminates in an upturned end portion over which the socket may be fitted, and a frame carrying the acid bottle, the piston latch and the cylinder and removably supported in the tank.

6. In a chemical mixing fire extinguisher system, a tank containing an alkaline solution, an invertible acid bottle, a piston latch normally holding the acid bottle in its upright position and operable by a pneumatic impulse to disengage the acid bottle, a cylinder for the piston latch, a projection extending across the top of the cylinder and having a socket at one end thereof and a duct extending between the socket and the cylinder, the piston of the piston latch having a projection to engage in and seal the mouth of the duct when the piston latch is in its uppermost position, a pipe section arranged in the distributing pipe and having a branch which projects laterally from the distributing pipe into the tank and terminates in an upturned end portion over which the socket may be fitted, and a frame carrying the acid bottle, the piston latch and the cylinder and removably supported in the tank.

7. The combination with a dry pipe chemical mixing system which includes a tank containing an alkaline solution, a distributing pipe leading therefrom, an acid bottle arranged to discharge its contents into the tank, and a by-pass connection affording a restricted communication between the distributing pipe and the tank, of a part operable by a pneumatic impulse to provide for the discharging operation of the acid bottle and constructed to seal the by-pass when operated.

In testimony whereof I have hereunto set my hand in presence of two subscribing witnesses.
